(57) **CLAIM**

The ornamental design for a paint roller, as shown and described.

DESCRIPTION

FIG. 1 is a front, left perspective view of a paint roller showing my new design;

FIG. 2 is a right side view thereof;

FIG. 3 is a left side view thereof;

FIG. 4 is a rear view thereof;

FIG. 5 is a front view thereof;

FIG. 6 is a top plan view thereof; and,

FIG. 7 is a bottom plan view thereof.

The shade lines indicate the character and contour of the surfaces represented, not to be confused with surface ornamentation.
